Edgar M. Kitchin
his ATTORNEY.

UNITED STATES PATENT OFFICE.

OTTO B. WUNSCHOW, OF CHATTANOOGA, TENNESSEE.

BRAKE SHOE.

Application filed December 31, 1923. Serial No. 683,675.

To all whom it may concern:

Be it known that I, OTTO B. WUNSCHOW, a citizen of the United States, residing at Chattanooga, in the county of Hamilton and State of Tennessee, have invented certain new and useful Improvements in Brake Shoes; and I do hereby declare the following to be a full, clear, and exact description of the invention, such as will enable others skilled in the art to which it appertains to make and use the same.

This invention relates to improvements in brake shoes and re-inforcements therefor, and has for its primary object the production of a shoe of maximum stability which will remain true and hang accurately relative to the wheel and be effective even when worn down to the re-inforcing means.

With this and further objects in view as will in part hereinafter become apparent and in part be stated, the invention comprises certain novel constructions, combinations and arrangements of parts as subsequently specified and claimed.

25 In the accompanying drawings,—

Figure 1 is a view in side elevation of a brake shoe embodying the features of the present invention.

Figure 2 is a top plan view thereof.

30 Figure 3 is a perspective view of the back and key loop detached.

Figure 4 is a transverse section taken approximately midway of the length of the structure as seen in Figures 1 and 2.

35 Figure 5 is a fragmentary section through the back and loop detached, the parts being seen on an enlarged scale.

Figure 6 is a view similar to Figure 5 of a slightly modified embodiment.

40 Figure 7 is a fragmentary, inverted plan of the central portion of the back and loop, part being broken out for showing structure below.

Referring to the drawing by numerals, 45 1 indicates a wrought plate, preferably of malleable steel, formed with its edges beveled, at 2, 2, for bonding purposes, and also formed with longitudinal slots 3, 3, each of which is surrounded by beveled edges 4 for increasing the effectiveness of the bond. Approximately midway of the length of the plate 1, the same is formed with a longitudinal slot 5 through which extends a 50 loop 6 of material similar to plate 1, and 55 designed to provide an accurate key-way

for the attaching lug hereinafter mentioned.

The loop 6 is formed of a strip of material bent into U-shape with the legs bent outward beneath the plate 1, and the plate 60 1 is formed with notches or recesses 7, 7, opening into the slot 5 for accommodating the vertical or leg portions of the loop 6. The recesses 7 insure accurate assemblage 65 of the loop within the plate 1 in the first instance, and also serve to prevent any edge-wise movement of the loop during subsequent operations. The said notches, therefore, in initially locating and subsequently retaining the loop in place during casting, 70 prevent distortion or oblique location of the loop 6, which insures an accurate key-way and a consequent true and accurate hanging of the brake shoe.

The plate 1 is formed by any of the well 75 known methods, and the slot 5 with the recesses 7 is preferably stamped through the plate 1, or otherwise formed in a quick and inexpensive manner, so that there may at times appear a slight looseness between the 80 loop 6 and engaged recesses. To avoid any possible dislocation of the loop 6 during the subsequent casting operation, the underlapping, outwardly-turned portions 8, 8, of the loop are preferably anchored to the 85 plate 1 after the loop has been located in any of various acceptable ways, as, for example, by the spot welding indicated at 9 in Figure 5. A rivet or like connecting member, such as seen at 10 in Figure 6, 90 may be employed when preferred in lieu of the spot welding. As the balance of Figure 6 shows a structure identical with Figure 5, the reference numerals above used and the foregoing description will apply.

When the parts have been assembled, as seen in Figure 3, and the loop 6 anchored to the plate 1, the plate is inverted to the position seen in Figure 7, and in this position is introduced into a mold which is closed and the molten iron is then poured in to form the completed brake shoe 11, as seen in Figures 1, 2 and 4. This brake shoe may be of various sizes, contours and dimensions, but always preferably conforming with the requirements of the Master Car Builders' Association so as to fit the standard brake heads. The cast metal, as clearly seen in Figures 1, 2 and 4, covers 100 the end portions of plate 1 and effectively 105 110

bonds through the slots 3, overlapping the beveled edges 4 and also overlapping the beveled edges 2. The cast metal also fills in the space between the legs of the loop 5 and rises through the slot 5, forming a solid filler above the plane of the adjacent upper surfaces of plate 1, leaving only a key-way 12, and, outside of the loop 6, the cast metal extends above the loop and overlies a part of the cross plate thereof, leaving only the requisite portion of such plate exposed for effective engagement with the brake hanger. Thus the attaching lug 13 is formed of maximum stability with the key-way 12 formed with that precision and accuracy assuring the hanging of the brake shoe in exactly the proper relation to be most effective in engaging the wheel. In structures heretofore produced, the malleable loops employed have not been accurately maintained in place, and an angularly or oblique relation of the shoe relative to the wheel has followed, which has been especially detrimental to the effective brake action and production of rapid wear and early necessity for discarding such shoes.

Also it has been suggested heretofore that a brake shoe back of malleable material be employed with a central slot for the introduction of a hanger loop, which slot should be of a length equal to or greater than the length of the core employed for preserving the key-way in the loop during the casting operation. Such an enlarged, central slot in the backing plate has, of course, facilitated introduction of the said core, but in most instances the result was a failure to obtain effective bonding about the central area of the back and the production of objectionable sand holes. The present invention provides a slot 5 of a length less than the actual length of the core to be introduced which must at least be as long or longer than the thickness of the hanger lug 13. The slot 5 is, therefore, made, as best seen in Figure 7, slightly longer than the width of the material of loop 6, so that the core may be introduced after the plate 1 and loop 6 has been placed in the mold by having the end of the core inserted between the loop, down through the slot 5 to a point with the lower end beyond the adjacent end of the slot, then lowering the upper end of the core and moving the core back until it rests centered upon the surface of the cross bar of loop 6. Thus the slot 5 while of greater length than the width of the material of loop 6 is of less length than the thickness of the base of the hanger lug 13, that is, in other words, the slot 5 is of less length than the core to be introduced and insures a condition, when the molding operation is begun, which guarantees the production of an effecting bonding between the cast portions of the shoe and

the malleable portions therof, and also the formation of a lug 13 susceptible of withstanding a maximum of hard usage.

Certain brake shoes now in use employing wrought or malleable iron loops embedded in their hanger lugs have been found to have such loops inaccurately located, either initially or from displacement after the parts have been positioned in the mold, with the result that the final product has not been acceptable because of lack of capacity to fit the M. C. B. brake head. Some foundries have shown a loss of cast shoes as high as ten per cent of the production incident to such defects. Such loss is totally eliminated by the present invention. Furthermore, in types of shoes already in use, the key-ways have been found in instances to be too large, allowing the shoes to assume an angular relationship and ride diagonally on the periphery of the wheel. Such a condition is impossible with a brake shoe embodying the features of the present invention. In other constructions of brake shoes wherein a backing plate and malleable loop for the hanger lug have been employed, the fitting in of the core employed to produce the key-way has resulted in the crushing of the sand of the core, leaving floating sand producing defective shoes. Such constructions have also been found objectionable from the presence of fins which have to be clipped and ground after the tumbling operation. The provision for the effective core insertion in the present invention both eliminates danger of floating sand, and enables such precision of fit of the parts of the mold as to obviate fins, and assures the constant and uniform production of shoes which are ready for service as they come from the tumbler.

What I claim is:—

1. A brake shoe back comprising a reinforcing plate having a centrally located slot, and a hanger lug loop extending through the slot, the plate being formed with recesses opening into the slot for accommodating the legs of the loop.
2. In a brake shoe, the combination of a re-inforcing plate having a longitudinal slot, a hanger lug loop extending through the slot, a brake shoe body bonded with the plate and a brake shoe lug embedding parts of the loop, the slot being of greater length than the width of the material of the loop and of less length than the width of the lug.
3. In a brake shoe, the combination of a re-inforcing plate having a longitudinal slot, a hanger lug loop extending through the slot, a brake shoe body bonded with the plate and a brake shoe lug embedding parts of the loop, the slot being of greater length than the width of the material of the loop and of less length than the width of the lug, the material of the body of the

shoe extending into the loop beyond the plane of the back face of the body and forming an integral part of the lug.

4. A brake shoe comprising a reinforcing plate having a centrally located slot extending longitudinally of the plate, the plate being formed at each side of the slot with recesses extending along the slot and of a length less than the length of the slot, 10 and a loop having its legs extending through

said recesses, each recess being of a depth as great as the width of the respective leg of the loop for leaving the slot open and free throughout its length.

In testimony whereof I affix my signature ¹⁵ in presence of two witnesses.

OTTO B. WUNSCHOW.
